UNITED STATES PATENT OFFICE.

SAMUEL H. HARRINGTON, OF NEW YORK, N. Y., ASSIGNOR TO WILLIAM C. WILSON, OF NYACK, NEW YORK.

SIGNAL-LIGHT FOR RAILWAY SIGNALING, &c.

No. 918,541.

Specification of Letters Patent.

Patented April 20, 1909.

Application filed March 7, 1905. Serial No. 248,930.

To all whom it may concern:

Be it known that I, SAMUEL H. HARRINGTON, residing at New York, in the county of New York and State of New York, have invented certain new and useful Improvements in Signal-Lights for Railway Signaling, &c., of which the following is a full, clear, and exact description, such as will enable others skilled in the art to which it appertains to 10 make and use the same.

This invention relates to signal lights.

One of the objects thereof is to provide a construction wherein a signal glass may be so positioned as to perform its functions with 15 a maximum of efficiency and yet the source of light be located in a convenient and safe position.

Other objects will be in part obvious and in part pointed out hereinafter.

20 The invention accordingly consists in the features of construction, combinations of elements and arrangement of parts which will be hereinafter described and the scope of which will be indicated in the following 25 claims.

In the accompanying drawings which illustrate one of various possible embodiments of my invention, Figure 1 is an elevation, shown largely in section along the line 30 $x-x$ of Fig. 2 in order to disclose the structure more clearly. Fig. 2 is a side elevation of the same.

Similar reference characters refer to similar parts throughout the several views.

35 This invention proposes, in so far as one of its features is concerned, the location of a signal glass on the upper portion of a signal supporting member or post having a source of light at the lower portion, and the provision of means whereby the radiation from 40 said source of light may be directed through said signal glass.

Referring now to Fig. 2, A represents a post or a lower portion, preferably provided 45 with a supporting column B which is adapted to be buried to any desired depth in the ground. By the expression "lower portion" as used in this description and in the following claims is meant that portion which 50 is within the reach of an ordinary person without artificial means of elevation.

Upon post A is mounted a column C which, in this embodiment, is formed of spiral strips

of metal riveted together as shown in the drawing and crowned by a cap D. A shaft 55 1 is journaled within bearings 2 in the upper portion of the post. By the expression "upper portion" as used in this description and the following claims is meant that portion which is at such an elevation as is adapted 60 for the efficient mounting of signals. Upon shaft 1 are fixed arms 3 and 4, adapted, upon the signal being set in a position indicating "danger", to assume a position substantially parallel to the axis of the post and 65 upon opposite sides thereof. Upon shaft 1 is also mounted a signal which, in this embodiment, is shown as a semaphore arm E and counterweight F and is operated by any desired means, not shown as it forms no part 70 of the present invention. The word "signal" as used throughout this specification and the following claims is used in a broad sense as denoting any means the condition of which is adapted to indicate a given state of facts. 75

The ends of arms 3 and 4 are circular in form and serve as frames for glasses 5. The glass in arm 3 is adapted when the signal is in "danger" position to register with an opening 6 in the side of the post which is 80 covered by a signal glass 7. These glasses may be colored in any desired way, preferably so as to emit by their joint action a red light to indicate "danger" and to give forth a green or white light when the signal 85 is in "safety" position. This is accomplished in the above embodiment by having at 7 a white glass and at 5 a red glass. Obviously, if desired, another arm may be fixed to shaft 1 bearing a green glass and 90 adapted to register with opening 6 when the signal is in "safety" position and vary the color of the light emitted thereby. By the word "emit" as used throughout the following claims is meant to radiate beyond 95 the confines of the signal post. Obviously, this will be chiefly through signal glass 7.

Arm 4 is provided with a glass in a similar manner and is adapted to co-act with an opening 8, preferably diametrically opposite opening 6. This opening, together with the glass 8^a which covers the same, form what may be termed a "back light" and that expression is used herein to denote an auxiliary light the rays of which are 105 directed in a direction different from that

in which the majority of the rays of the main signal light travel.

Within the post A is mounted, by any suitable means of support, a source of light 9. This is shown as an oil lamp, but may 5 obviously be of any other type. The light 9 is so placed with respect to a vertically mounted reflector 10 that its rays will be radiated from a point substantially at the 10 focus thereof. This will result in a vertical reflection and if, as is preferably the case, a parabolic reflector is used, the rays will be reflected in substantially parallel lines. Opposite opening 6 and at an angle 15 of substantially 45° with the axis of the post is a mirror 11. This mirror is adapted to throw the majority of the light through signal glass 7. The lower portion of the mirror, however, is cut away and a suitable 20 inclosing member 12 conducts a portion of the light through the back light. The member 12 may be silvered, if desired, to economize the light and direct the same through the opening 8. A door 13 is preferably located in the lower portion A through which lamp 9 may easily be reached.

The operation of the above embodiment of my invention should be largely obvious. The majority of the light from a source of 30 light placed in the position indicated in Fig. 1 is directed by the inclined mirror 11 and member 12 through the openings 6 and 8 respectively. Under normal "safety" condition this light is allowed to pass freely 35 and serves to indicate the track conditions.

When it is desired to place the signal in "danger" condition, however, the shaft is rotated until the glasses carried by arms 3 and 4 register with openings 6 and 8 and the 40 light is transmitted through the same and the color thereof changed.

It will thus be obvious that I have provided a signal device whereby the light is economically used and is emitted at a point 45 at which its action is most efficient and yet the source of light is within reach whereby it may conveniently receive any necessary care and attention. It will also be seen that the several parts are simple and durable and are adapted to perform efficiently 50 the functions for which they are designed. Moreover, the location of the source of light protects it under all weather conditions and hence renders its action more 55 reliable. Also, the construction of the signal post combines lightness with stiffness and strength.

As many changes could be made in the 60 above construction and many apparently different embodiments of my invention could be made without departing from the scope thereof, I intend that all matter contained in the above description and shown in the accompanying drawings shall be interpreted 65 as illustrative and not in a limiting sense.

I desire it also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent, is:—

1. In combination, a semaphore, a support for the same, a source of light within said support, and means carried by said semaphore adapted to vary the color of the light emitted through a plurality of openings in 80 said support.

2. In combination, a semaphore, a support for the same, a source of light inclosed by said support, a plurality of glasses adapted to permit a passage of light from said source, and means carried by said semaphore adapted simultaneously to vary the color of the light emitted through said glasses.

3. In combination, a semaphore, a support for the same, a source of light inclosed by 90 said support, said support being provided with openings in its opposite sides to permit the passage of light therethrough and co-acting glasses carried by said semaphore adapted to vary the color of the light emitted 95 through said openings.

4. In combination, a signal glass, a source of light, and means whereby the light from said source may be directed vertically from said source and horizontally through said 100 signal glass.

5. In combination, a signal glass, a source of light, and means whereby the light from said source may be directed in one direction from said source and in another direction 105 through said signal glass.

6. In combination, a signal support, a signal glass in the upper portion thereof, a source of light in the lower portion thereof, and means adapted to direct the light from 110 said source through said signal glass.

7. In combination, an upright support having in its upper portion a signal glass, a source of light, and a mirror adapted to direct the light from said source through said 115 signal glass.

8. In combination, an upright support having in its upper portion a signal glass, a source of light, and an inclined mirror adapted to direct the light from said source through 120 said signal glass.

9. In combination, an upright support having in its upper portion a signal glass, a source of light, and a mirror set at an angle of substantially 45° with said signal glass 125 adapted to direct the light from said source of light through said signal glass.

10. In combination, an upright signal support having in its upper portion a main signal glass, and a back light and having a source 130

of light positioned therein, and means adapted to direct the light from said source through said main signal glass and said back light.

11. In combination, an upright signal support having in its upper portion a main signal glass, and a back light and having a source of light positioned therein, and a mirror adapted to direct the light from said source through said main signal glass and permit the same to 10 pass through said back light.

12. In combination, an upright signal support having in its upper portion a main signal glass, and a back light and having a source of light positioned therein, and an inclined 15 mirror adapted to direct the light from said source through said main signal glass and permit the same to pass through said back light.

13. In combination, an upright signal support having in its upper portion a main signal glass, and a back light and having a source of light positioned therein, and an inclined 20 mirror adapted to direct the light from said source through said main signal glass and 25 provided with an opening adapted to permit the same to pass through said back light.

14. In combination, a signal support, a signal glass in the upper portion thereof, a source of light in the lower portion thereof, a 30 parabolic reflector adapted to co-act with said source of light, and means adapted to direct the light from said source through said signal glass.

15. In combination, an upright signal support having therein a signal glass, a source 35 of light, a mirror adapted to direct the light from said source through said signal glass, and a semaphore mounted upon said support and provided with means adapted to co-act 40 with said signal glass.

16. In combination, a signal support having therein a main signal glass, a back light, a source of light, and a parabolic reflector adapted to co-act with said source of light, 45 and means adapted to direct the light from said source of light through said main signal glass and said back light.

17. In combination, a signal support, a signal glass in the upper portion thereof, a 50 source of light in the lower portion thereof, and a mirror adapted to direct the light from said source through said signal glass.

18. In combination, a signal support, a signal glass in the upper portion thereof, a 55 source of light in the lower portion thereof, and an inclined mirror adapted to direct the light from said source through said signal glass.

19. In combination, a signal support having therein a signal glass, a source of light, a mirror adapted to direct the light from said 60 source through said signal glass, and a semaphore carried by said support having means adapted to vary the light emitted.

65 20. In combination, a signal support hav-

ing therein a signal glass, a source of light and an inclined mirror adapted to direct the light from said source through said signal glass, and a signal carried by said support having means adapted to vary the light emitted. 70

21. In combination, a signal support having therein a back light, a main signal glass, a source of light and an inclined mirror adapted to direct the light from said source through said main signal glass, and a signal 75 carried by said support having means adapted to vary the light emitted.

22. In combination, a signal support having therein a main signal glass, a source of light, a back light, a parabolic reflector 80 adapted to co-act with said source of light and an inclined mirror adapted to direct the light from said source through said main signal glass and permit the same to pass through said back light, and a signal carried by said 85 support having means adapted to vary the light emitted.

23. In combination, a signal support having therein a main signal glass, a back light, a source of light and an inclined mirror adapted to direct the light from said source through said main signal glass and permit the same to pass through said back light, and a signal carried by said 90 support having means adapted to vary the light emitted. 95

24. In a device of the class described, a signal support having within the upper portion thereof a main signal glass, an inclined mirror and a back light, and in the lower portion thereof a source of light and a parabolic 100 reflector adapted to co-act therewith, said mirror being so related to said source of light as to direct a portion of the radiation therefrom through said main signal glass and permit a portion thereof to pass through said 105 back light.

25. In a device of the class described, in combination, a signal support having within the upper portion thereof a main signal glass, an inclined mirror and a back light, and in the lower portion thereof a source of light and a parabolic reflector adapted to co-act therewith, said mirror being so related to said 110 source of light as to direct a portion of the radiation therefrom through said main signal glass and to permit a portion thereof to pass 115 through said back light, and a signal carried by said support adapted to vary the light emitted.

26. A signal post formed of spiral strips of 120 metal, the adjacent edges thereof being riveted together.

27. In combination, a signal, a support for the same formed of spiral strips of metal, a source of light within said support, and 125 means carried by said signal adapted to vary the color of the light emitted thereby.

28. In combination, a signal, a support for the same formed of spiral strips of metal, a source of light inclosed by said signal, and 130

co-acting glasses carried by said signal adapted to vary the color of the light emitted thereby.

29. In combination, a signal support formed of spiral strips of metal and having therein a signal glass, a source of light and a mirror adapted to direct the light from said source through said signal glass, and a semaphore carried by said support having means adapted to vary the light emitted.

30. In a device of the class described, a signal support formed of spiral strips of metal and having within the upper portion thereof a main signal glass, an inclined mirror and a back light, and in the lower portion

thereof a source of light and a parabolic reflector adapted to co-act therewith, said mirror being so related to said source of light as to direct a portion of the radiation therefrom through said main signal glass and permit a portion thereof to pass through said back light.

In testimony whereof I affix my signature, in the presence of two witnesses.

SAMUEL H. HARRINGTON.
